UNITED STATES PATENT OFFICE.

CHARLES L. RAYFIELD, OF CHICAGO, ILLINOIS.

CARBURETER.

1,307,457.

Specification of Letters Patent. Patented June 24, 1919.

Application filed June 21, 1917. Serial No. 176,185.

To all whom it may concern:

Be it known that I, CHARLES L. RAYFIELD, a citizen of the United States, residing at Chicago, in the county of Cook and State 5 of Illinois, have invented certain new and useful Improvements in Carbureters, of which the following is a specification.

My invention relates to thermally controlled carbureters.

10 One of the objects of my invention is to provide means for automatically controlling the intake of an internal combustion engine, whereby to provide suitable qualities of the fuel charges, used in starting an engine when 15 the engine and its fuel are cold, to compensate for the results produced by such conditions.

Another and more specific object of my 20 invention is to provide means to automatically vary the operation of a carbureter for producing the fuel charges, for an internal combustion engine at time of starting when the engine is cold, by means that is responsive to the temperature of the engine 25 which will cause suitable variations of conditions to provide proper mixture, until the desired quality of the charge has been obtained, for the normal running temperature of the engine.

30 Still another object of my invention is to provide means to yieldingly resist the opening of the auxiliary air valve of the carbureter, when the engine is cold, and which will reduce the resistance to the operation of 35 said valve as the temperature of the engine rises.

Other, further and more specific objects 40 of my invention will become readily apparent, to persons skilled in the art, from a consideration of the following description when taken in conjunction with the drawings, wherein:—

Figure 1 is a central vertical section of a conventional carbureter and my thermo device for varying the resistance to operation 45 of the air admitting valve.

Fig. 2 is a fragment of a radiator of an automobile showing one means for arranging the device to be influenced by the heat 50 of the engine.

In all the views the same reference characters are employed to indicate similar parts.

When starting an internal combustion engine its temperature is below its efficient operating temperature. At such time the liquid fuel, such as gasolene, is below the tempera-

ture at which it is maintained during the normal working operation of the engine. When the liquid fuel is cold it is more viscous than when it is warm, therefore, the 60 same quantity of such fluid will not pass through a given orifice under the same pressure. It follows, then, that a smaller portion of fluid, or gasolene, passing through a fixed orifice, other conditions being unchanged, will provide an attenuated or sub-normal mixture of a quality below that required for normal operation. When cold the air is heavier than when warm, that is to say, it is specifically heavier, therefore, a 70 given volume of air which will pass through a given orifice under a given pressure will be of greater mass than when it is warmer.

It is the mass of air and not its volume 75 that determines its oxygen content and it is the proportion of oxygen to hydrocarbon that determines the quality of mixture and not the volume of air per given volume of gasolene. From the above statement it will be readily deduced that with a carbureter adjusted for 80 normal operation, there will be admitted into the cylinders of an engine a smaller quantity of gasolene and a greater quantity of oxygen at the time when the engine is being started, thus producing a lean or sub-normal attenuation of the fuel charges.

To automatically take care of the changed condition due to variations in temperature, I may use an imprisoned volatile fluid having a critical temperature expansion, such 90 as tetra-chlorid or carbon, ether, alcohol, gasolene, or the like, or I may use confined air, as the transmitting medium.

In the accompanying drawings I have 95 illustrated one embodiment of my invention for the purpose of clear disclosure, reserving, however, to myself, the right to change or vary the structure to any extent, or in any direction within the scope of the appended claims.

The casing 5 incloses the mixing chamber 6, the float chamber 7, and the chamber 8, within which the temperature responsive device 9 is contained. In the specific showing this device takes the form of a bellows diaphragm, capable of considerable relative, axial elongation and contraction. It is airtight and is connected by a pipe 10 to an airtight air chamber 11. It may be filled with air or a suitable volatile liquid or expansible 105 gas.

The chamber 11, to be responsive to the

heat of the engine, may be submerged in the cooling water 12, in the radiator 13, or placed therein, within the influence of the vapor arising from the water, or it may be 5 otherwise secured to or associated with the engine, within the influence of the heat produced thereby, whereby its content may be heated and thereby cause it to expand by the effect of the rising temperature of the engine. It is not essential to the operation of the device, therefore, that the chamber 11 be placed actually within the radiator or influenced by the cooling water, as the desideratum is, that the rising temperature of the 10 engine shall serve to heat the content of the device, whether the heat be applied directly or indirectly thereto.

The air intake 14 of the carbureter is normally closed by an air valve 15. The spring 20 16, which moves the valve toward closed position, may be adjusted by the bearing nut 17, which surrounds the valve stem 18, and by which the valve stem is guided. A supplemental spring 19 connects the valve 15 25 to the axially movable diaphragm structure 9. This spring tends to close the valve, when the diaphragm is contracted, as shown, and in this respect it supplements the action of the valve spring 16. The valve is therefore 30 yieldingly held closed by the combined action of the springs 16 and 19 when the expansible medium within the chamber 11, and the diaphragm structure, is below a given temperature. When the imprisoned 35 expansible medium is heated, as by the temperature of the engine, the diaphragm structure 9 will be expanded, thereby relaxing the spring 19, which will consequently reduce the stress with which the valve 15 is held 40 closed, thus rendering the valve 15, more easily operable by the suction effect of the engine.

20 is the spraying nozzle of the carbureter, in communication with the liquid-containing 45 float chambers 7, by an opening 21. A needle valve 22 may be used to control the flow of gasoline into the nozzle. 26 is the throttle.

Primary air passages, around the nozzle, 50 are provided by the openings 23 of which there may be any desired number of suitable size.

A float 24 controls the quantity of liquid fuel in the float chamber, as usual in such 55 devices.

The operation of the device is as follows:—When the engine is cold, the air or other expansible fluid or gas within the casting 11 is cool and contracted, causing contraction 60 of the diaphragm structure 9. The decrease in volume of the confined medium, resulting from the reduction of temperature, supplemented by the external atmospheric pressure will cause contraction of the diaphragm. This, of course, as heretofore ex-

plained, increases the tension of the spring 19. When the engine shaft is initially rotated, in the act of starting the engine, it will require greater suction to be produced by the engine to open the valve 15, to the same extent as such operation is now opposed by the combined resistance imposed by the springs 16 and 19. Consequently a mixture of suitable quality will be drawn 70 into the cylinder, as air will be taken in largely through the primary air ports 23. After the engine has been operating for a while, its increased temperature will heat the cooling water which in turn will heat and expand the content of the casing 11 75 causing the free end of the diaphragm 9 to be moved downwardly, thereby reducing the tension of the spring 19, whereupon the air supply valve 15 will be more easily opened, to supply the proper proportion of air for 80 the normal running of the engine. By this means compensation is made for the reduced temperature of the engine, fuel and air, at the time of starting and during the time when the temperature of the engine is below 85 that at which it is most efficiently operative, the charge mixture being automatically maintained against varying conditions of fuel temperature as the temperature of the 90 engine increases.

The thermo-responsive controlling device compensates in some measure, for variation in viscosity of the liquid fuel due to changes in atmospheric temperature while the engine is running. In cold weather the engine radiates a greater quantity of heat, and while viscosity of the fuel in such weather is greater, greater resistance to the opening of the air valve 15 will be interposed by the 100 operation of the thermo-regulator. Therefore, in this example, under the same conditions of operation of the engine, the quality of mixture will be maintained substantially constant which, otherwise, would be more attenuate in cold weather than would 105 obtain when the weather is warmer.

In order that the rise of engine temperature may not too quickly act upon the controlling device, the chamber 11 may be placed inside of the radiator, so that the 110 cooling water will have the effect of producing the desired results, in order that charges of uniform quality may continue to be introduced into the engine before and after it becomes fully warmed up and otherwise capable of doing its normal work.

Having described my invention, what I claim is:—

1. A carbureter having a valve to admit air and a valve spring tending to hold said valve closed, in combination with a device responsive to engine temperature and means operable thereby to supplement the effect produced by said spring.

2. A carbureter having a valve to admit

air operable to be opened by the suction of an engine and a spring tending to close said valve, in combination with a temperature-responsive device to be heated by an engine 5 and connected to said valve by a supplementary spring to assist the action of the valve spring tending to hold the valve closed when the temperature of the engine is below that acquired during normal operation 10 and adapted to relax said supplementary spring when the temperature of the engine rises.

3. A carbureter having an intake valve; yielding means to normally hold said valve closed; mechanically-operable means for supplementing the valve closing means and means extending from said mechanically-operable means to said engine to move the former, thereby to reduce opposition to 20 movement of said valve upon rise of temperature of the engine.

4. A carbureter having an intake valve; yielding means to normally hold said valve closed; mechanically-operable means for 25 supplementing the valve closing means; and a conduit, containing an expansible medium, extending from said mechanically-operable means to said engine to move said mechanically-operable means whereby to decrease resistance to movement of said valve when the 30 temperature of the engine is increased by its operation.

5. A carbureter having an intake valve; yielding means to normally hold the valve closed; an expansible easing to supplement the valve closing means, another casing subject to the heat of the engine, and a closed conduit connected to said casing, said easing and conduit hermetically closed and containing 35 an expansible fluid to vary the resistance

to movement of said valve by variation of temperature of said engine.

6. A carbureter having an intake valve and a fuel valve in combination with a movable temperature-responsive device; a casing, 45 containing an expansible medium, for inclusion within the radiator of an engine; a conduit connecting said casing to said temperature-responsive device, said device, casing and conduit hermetically sealed, and means, operable by the latter to resist opening of one of said valves, responsive to the temperature of the cooling water of the engine.

7. A carbureter having an auxiliary air 55 inlet and a valve therefor, primary means for normally holding said valve closed against suction of the engine, secondary means for assisting said primary means in holding the valve closed, a temperature responsive device subject to the heat of the engine connected to said secondary means for controlling the same.

8. A carbureter including an auxiliary air inlet and a valve therefor normally opened 65 by the suction of the engine, primary means comprising a spring for holding the valve closed against the suction of the engine, secondary means comprising an additional spring assisting said primary means in holding the valve closed, a temperature responsive device subject to the heat of the engine connected to said additional spring to regulate the tension thereof, whereby as the heat of the engine increases the resistance to the 70 opening of the valve by the suction of the engine will be decreased.

In testimony whereof I hereunto set my hand.

CHARLES L. RAYFIELD.
